VACUUM TYPE EXHAUST MUFFLER

Alton D. Flickinger, Inglewood, Calif.

Application March 14, 1944, Serial No. 526,446

1 Claim. (Cl. 181—43)

This invention relates to a vacuum type exhaust muffler, and has for one of its objects the production of a simple and efficient muffler especially adapted for use upon airplanes and the like, constructed to facilitate the discharge of exhaust gases from the muffler.

A further object of this invention is the production of a simple and efficient muffler so constructed as to efficiently eject exhaust gases from the muffler by passing a blast of air longitudinally through the center of the muffler from end to end and by providing lateral ports throughout the length of the muffler for extracting the exhaust gases by means of a vacuum which is created by air currents passing over the streamline surface of the muffler.

Other objects and advantages of the present invention will appear throughout the following specification and claim.

In the drawing:

Figure 1 is a side elevational view of the muffler;

Figure 2 is a longitudinal sectional view thereof;

Figure 3 is a sectional view taken on line 3—3 of Figure 1;

Figure 4 is a sectional view taken on line 4—4 of Figure 1;

By referring to the drawing, it will be seen that 10 designates the streamline body of the muffler which is provided with a forward tapering nose 11 having an air entrance opening 12 at the forward extremity thereof. An exhaust tube 13 connects the forward end of the body of the muffler with an engine of a suitable type and this tube communicates with the muffler exhaust entrance port 14 which is formed in one side of the body 10 near the air entrance opening 12 thereof. The exhaust tube 13 is secured to the muffler 10 in any suitable manner, such for instance, by means of the rivets 13^a which pass through the flange 13^b and the muffler body 10.

The body 10 bulges to a point rearwardly of the port 14 and then tapers toward the rear end 15 of the body 10. The rear end 15 is provided with a discharge opening 16 which is in direct line with the air entrance opening 12. It should thereby be noted that as the airplane or other means is driven forwardly, a central current of air will pass in through the opening 12, then longitudinally of the body 10 and will be discharged out through the rear discharge opening 16, thereby drawing exhaust gases longitudinally of and out through the body 10.

The receding outer wall of the body 10 is provided with a plurality of exhaust apertures 17 aligned circumferentially and also longitudinally of the body, as shown in Figures 1 to 3, of the

drawing. Consequently, as the muffler is carried forwardly, air currents will pass over the forward surface of the nose of the muffler and will then be deflected from the tapering rear or receding portion of the body. This will build-up a vacuum around the outer surface of the tapering rear portion of the body 10, thereby causing the exhaust gases within the body 10 to have or to be drawn out through the ports 17 from the interior 10 of the muffler body 10. It will, therefore, be seen that I have provided two distinct scavenging means for the muffler to extract or to cause the exhaust gases to be discharged from the muffler. The central longitudinal blast will tend to draw the exhaust from the exhaust tube 13 into the muffler and then drive these gases longitudinally of and out through the rear end of the muffler. At the same time the vacuum which is built-up around the exterior of the muffler will cause the exhaust gases to leave through the lateral apertures 17.

From the foregoing description it will be seen that a very simple muffler is provided having a minimum number of parts, and which may be manufactured and maintained at a minimum expense. It should be understood that the muffler may be mounted and supported in any suitable or desired manner, and since the present invention resides in the construction of the muffler itself, no attempt is made to illustrate mountings and other auxiliary parts which may be used with the muffler. Furthermore, it should be understood that certain changes in detail construction may be made without departing from the spirit of the invention so long as these changes fall within the scope of the following specification and claim.

Having described the invention, what I claim as new is:

40 A muffler of the class described comprising a one-piece stream-line body, said body having a lateral exhaust gas entrance port near its forward portion, said body being gradually enlarged in its transverse area from the forward portion to a point intermediate the ends of the body to provide a relatively large midway portion, said body tapering toward the rear end thereof, said body having a plurality of vacuum ports in the tapering rear portion, said ports being located in an area of the body smaller in its transverse dimension than said midway portion to cause gases to be drawn by vacuum pull through said vacuum ports as the muffler is carried in a forward direction to cause a vacuum pull of the air rushing exteriorly and longitudinally of the body, and said body having forward and rear centrally located air inlet and outlet ports.
